METHOD OF INSERTING SINGLE SHEETS INTO FOLDED SHEETS AND APPARATUS FOR PERFORMING THE SAME

Herman Dann, Brooklyn, N. Y.

Application March 17, 1952, Serial No. 277,016

6 Claims. (Cl. 270—57)

1

This invention relates to the method of inserting a single sheet into a folded sheet and the apparatus for performing the same.

In the process of preparing printed material it frequently becomes necessary to insert a single sheet within a folded sheet. Heretofore this process has either been done by hand, which with the present high cost of printing labor has been most unsatisfactory, or has been performed by complicated and cumbersome machinery, which has been extremely costly, has operated at a slow speed, and has been very apt to go out of order.

It is an object of this invention to produce a method of inserting a single sheet into a folded sheet which will be simple and which will be low in cost.

It is a further object of this invention to produce an apparatus for performing the above method which will be relatively rapid in operation.

Briefly stated the invention embodies the method of inserting a single sheet into a folded sheet which comprises placing the single sheet behind the folded sheet, raising the upper side of the folded sheet, inserting the single sheet between the upper and lower sides of the folded sheet, and thence lowering the upper side of the folded sheet. The folded sheet, which now has the single sheet inserted in it, may then be conveyed to an appropriate receptacle.

The method is preferably performed with a series of single and folded sheets, so that a number of single sheets can be inserted, one by one, into each of a number of folded sheets.

The method may also include means for placing a number of single sheets and a number of folded sheets into respective piles, and means for equalizing the heights of said piles.

The invention will now be described by reference to the accompanying drawings which are made a part of this specification and which show one form of the apparatus which may be used to carry out this invention. It is pointed out, however, that various changes and modifications of this invention can obviously be made within its spirit and scope and will occur to those skilled in this art.

Fig. 1 is a side view of one form of the apparatus which may be used to carry out this invention with the suction cut-off device and the lines used in the same omitted for clarity of illustration.

Fig. 2 is a top view of the form of the apparatus shown in Fig. 1.

Fig. 3 is a side view of the apparatus shown in Fig. 1 showing the other side of the device.

2

Fig. 4 is a sectional view of the apparatus taken on lines 4—4 of Fig. 3.

Fig. 5 is a sectional view of the timing control used in this invention taken on lines 5—5 of Fig. 1.

Fig. 6 is a sectional view of the means used to adjust the size of the receptacle for folded sheets of the apparatus shown in Fig. 1 taken on lines 6—6 of Fig. 3.

Fig. 7 is a sectional view showing details of the portion of the apparatus used to insert the single sheet into the folded sheet taken on lines 7—7 of Fig. 1.

Fig. 8 is a sectional view showing further details of the apparatus used to insert the single sheet into the folded sheet taken on lines 8—8 of Fig. 7.

Fig. 9 is a sectional view showing further details of the means used to adjust the size of the receptacle for folded sheets to the size of the folded sheets to be used in the apparatus taken on lines 9—9 of Fig. 3.

Figs. 10—13 show the various steps and movements of the apparatus shown in Fig. 1 in the process of inserting a single sheet into a folded sheet.

Fig. 14 is a side view identical with Fig. 1 but showing the suction cut-off means which were omitted from Fig. 1.

Fig. 15 is a detail view showing the method of operation of the suction cut-off means.

Fig. 16 is a detail view of the suction pipe used in this invention.

Referring now to the specific form of the invention shown in the drawings, there are provided receptacle 10 for single sheets and receptacle 11 for folded sheets. Receptacle 10 is located to the rear of receptacle 11. It must be understood that the terms "behind," "front," and "rear" as used in this specification relate to the direction in which the single and folded sheets travel in the apparatus used to carry out this invention and no other meaning of the terms is intended.

Receptacles 10 and 11 are designed to hold a number of single sheets 12 and folded sheets 13, these sheets being piled on top of each other in a flat position in the respective receptacles and the fold 14 of the folded sheet lies to the rear of receptacle 11.

Receptacles 10 and 11 are adjustable in height by means of the raising and lowering of base portions 15 and 16 of receptacles 10 and 11 by means of handles (not shown) which control gears (not shown), which gears are secured to chain drives (not shown) which chain drives

raise and lower base portions 16 and 15. In addition base portions 15 and 16 are raised during the operation of this device so that the height of the pile of sheets is kept constant even though some are removed from the pile by means of the conventional pile height control. This control is conventional in this type of machine and is well known to those skilled in this art.

Feed rollers 19 and 20 are located in front of receptacle 10. Feed roller 19 is driven by shaft 20 which bears gear 21 and bevel gear 22. Gear 21 drives intermediate gear 23 which in turn drives gear 24. Gear 24 is secured to shaft 25 which in turn drives feed roller 20.

Bevel gear 22 is driven by bevel gear 26 which is secured to shaft 27. Shaft 27 also bears bevel gear 28. Bevel gear 28 is driven by bevel gear 29 which in turn is secured to shaft 30. Shaft 30 drives feed roller 31. Shaft 30 also bears gear 32 which drives intermediate gear 33. Intermediate gear 33 drives gear 34 which is secured to shaft 35. Shaft 35 drives feed roller 36.

Shaft 30 also bears pulley 37. Pulley 37 carries belt 38 which is also secured to pulley 39. Pulley 39 is secured to shaft 40. Shaft 40 also bears sprocket 41 which bears chain 42. Chain 42 also meshes with sprocket 43 which is secured to shaft 44. Shaft 44 also bears eccentrics 45 and 46 which control the timing of this device as will be subsequently explained.

Shaft 40 also bears flywheel 47 which bears belt 48. Belt 48 is secured to pulley 49 which in turn is secured to motor 50. Motor 50 is secured to the base 51 of this device by means of screws 52.

In order to secure better contact of sheets 12 and 13 with rollers 19, 20, 31 and 36 additional free moving rollers 53 and 54 are provided over feed rollers 19 and 20 and additional roller 55 is provided over feed roller 36. These free moving rollers are driven by contact with the driven rollers.

In the operation of this apparatus it is highly desirable, as will be subsequently shown, to adjust the size of the receptacle for the folded sheets to the size of the folded sheets used. For this reason pillar 56 is made moveable and is capable of sliding on rails 57 and 58. Lock 59 is provided to hold pillar 56 in position after it is adjusted to the point desired. Lever 60 is used to control the position of pillar 56. Lever 60 is pivoted to the base of the machine and is also connected to arm 61 which is in turn secured to arm 62 which in turn is secured to pillar 56.

The specific operation of this device will now be explained.

Moveable suction feet 63 are disposed above receptacle 10 for single sheets. In the preferred modification three of these devices are set up alongside each other. Additional moveable suction feet 64 are disposed above receptacle 11 for folded sheets. In the preferred modification two of these devices 64 are set up alongside each other. Suction feet 63 are secured to pipe members 65 by clamp members 66. Clamp members 66 are secured to shaft 67.

Suction feet 64 are secured to pipe members 68 by clamp members 69 which are in turn secured to shaft member 70. Shaft members 67 and 70 are designed to move suction feet 63 and 64 upwardly, downwardly and laterally as will be subsequently shown. The upward and downward movements of suction feet 63 and 64 are identical since they are controlled by the same timing device as will be now shown.

Arm 71 is secured to shaft 61, arm 71 is also secured to arm 72 by pin 73. Arm 72 is secured to arm 75 by pin 74. Arm 75 is controlled by cam 76 which is secured to shaft 77.

Shaft 77 also bears cam 78 which controls arm 79 which is secured to arm 80 by pin 81. Arm 80 is also secured to arm 82 by pin 83. Arm 82 is secured to arm 71 by pin 84. Spring 84 is secured to pillar 56 and arm 79.

Shaft 77 also bears arm 85 which turns with shaft 77. Arm 85 is secured to arm 86 by pin 87. Arm 87 is secured to shaft member 70 and is also adapted to ride in recess 88 provided in guide 89. It is pointed out that guide 89 is preferably offset so that suction feet 64 will not rise directly vertically.

Shaft 77 is also secured to arm 90. Arm 90 is secured to arm 91 by pin 92. Arm 91 rides on the circumference of eccentric 45. Eccentric 45 has arm 93 riding upon its circumference. Arm 93 is secured to arm 94 by pin 95. Arm 94 is also secured to shaft 96 which bears cams 97 and 98. Cam 97 controls arm 99 which is secured to arm 100 by pin 101. Arm 100 is secured to arm 102 by pin 103. Arm 102 is secured to arm 105 by pin 104. Arm 105 is secured to shaft 106 which bears moveable suction feet 108 which are secured to shaft 106 by clamps 109. Clamps 109 also secure pipe members 110 to suction feet 108.

In the preferred modification two of these suction feet 108 are provided.

Arm 105 is also secured to arm 111 which is controlled by cam 98.

In the operation of the modification of the device shown using suction feeding it is desirable to cut the suction off when the moveable suction feet reach a point about $\frac{2}{3}$ from the top of their stroke. For this reason shaft 77 bears arm 112 which controls arm 113. Arm 113 is secured to arm 114 which in turn is secured to arm 115. Arm 115 controls door 116. Door 116, when it is open, breaks the suction to suction feet 63 and 64.

Shaft 96 also bears arm 117 which is in turn secured to arm 118. Arm 118 is secured to arm 119 which in turn is secured to door 120. Door 120, when it is open, breaks the suction to suction feet 108.

Figs. 14, 15 and 16 also show details of the means used to produce suction and air blast (when used) in this device. Motor 121 drives pump 122 which as both blower and suction ends 123 and 124. Pipes 125 and 126 are secured to the suction end 124 of pump 122. Pipes 125 and 126 after being secured to braking devices as were previously explained are secured to suction feet 63, 64 and 108.

With the description of the parts and functions thereof of the apparatus its operation can be easily understood.

Receptacle 10 is filled with single sheets and receptacle 11 is filled with folded sheets. The folded sheets are set so that the folds thereof are to the front of the receptacle so that the folded sheets are capable of opening forwardly. Pillar 56 is moved along rails 57 and 58 until the size of receptacle 11 is equal to the size of the folded sheets used. Lock 59 is then applied to hold pillar 56 in place.

Motor 50 is then turned on. Motor 121 controlling the suction feeds is then turned on but doors 116 and 120 are kept open. The heights of the piles of single and folded sheets are then equalized.

Door 116 is then closed manually and door 120 is kept open until the first single sheet is

inserted into the first folded sheet. As soon as that happens door 120 is closed and the subsequent opening and closing of doors 116 and 120 are controlled by the mechanism previously shown.

It can thus be easily seen that the use of this apparatus causes the single sheet to be picked up by suction feet 63, moved upwardly by the upward movement of the suction feet and carried over the feed rollers. At the same time suction feet 64 pick up one side of the folded sheet and move it upwardly so that the single sheet can be inserted. After this is done the side of the folded sheet raised is permitted to drop and the folded sheet, which now has the single sheet inserted into it, is picked up by suction feet 108 and carried to receptacle 150. The process is then repeated.

As the pile of single and folded sheets becomes lower the bottom portions 15 and 16 of receptacles 10 and 11 are raised.

This is done by the conventional pile height controls used in suction feeders. Since these devices are well known in the art they have not been put into the drawings of this specification. However, as shown in Figs. 10, 11, 12, and 13 pile height guide 151 lies on the top of the pile of sheets. When the pile is below a predetermined height, pile height guide 151 drops and controls gear and chain drives which raise the level of bottom portions 15 and 16 of receptacles 10 and 11.

I claim:

1. A device for inserting a number of single sheets into a number of folded sheets comprising a receptacle for the single sheets, a feed roll couple positioned forwardly of said receptacle for single sheets, a receptacle for folded sheets positioned forwardly of said feed roll couple, the topmost folded sheet disposed in said receptacle being positioned below a portion of the circumference of one of said feed rolls, an additional feed roll couple positioned forwardly of said receptacle for folded sheets, suction means located above said receptacle for single sheets, additional suction means located above said receptacle for folded sheets, arm members adapted to raise said suction means simultaneously, said arm members being actuated by the same timing mechanism so that the movement of said suction means is adapted to carry one of the single sheets at a time over said first-named feed roll couple and simultaneously to raise one side of one of said folded sheets so that one of said single sheets is inserted between the fold of one of said folded sheets, further suction means adapted to convey said folded sheets after insertion of said single sheets over said additional feed roll couple, an additional receptacle adapted to hold said folded sheets after insertion of said single sheets positioned forwardly of said additional feed roll couple, means driving said first-named feed roll couple and said additional feed roll couple, and means driving said suction means.

2. A device for inserting a number of single sheets into a number of folded sheets comprising a receptacle for the single sheets, a feed roll couple positioned forwardly of said receptacle for single sheets, a receptacle for folded sheets positioned forwardly of said feed roll couple, the topmost folded sheet disposed in said receptacle being positioned below a portion of the circumference of one of said feed rolls, means for adjusting the heights of said receptacle for single sheets and said receptacle for folded sheets, an

additional feed roll couple positioned forwardly of said receptacle for folded sheets, suction means located above said receptacle for single sheets, additional suction means located above said receptacle for folded sheets, arm members adapted to raise said suction means simultaneously, said arm members being actuated by the same timing mechanism so that the movement of said suction means is adapted to carry one of the single sheets at a time over said first-named feed roll couple and simultaneously to raise one side of one of said folded sheets so that one of said single sheets is inserted between the fold of one of said folded sheets, further suction means adapted to convey said folded sheets after insertion of said single sheets over said additional feed roll couple, an additional receptacle adapted to hold said folded sheets after insertion of said single sheets positioned forwardly of said additional feed roll couple, means driving said first-named feed roll couple and said additional feed roll couple, and means driving said suction means.

3. A device for inserting a number of single sheets into a number of folded sheets comprising a receptacle for the single sheets, a feed roll couple positioned forwardly of said receptacle for single sheets, a receptacle for folded sheets positioned forwardly of said feed roll couple, the topmost folded sheet disposed in said receptacle being positioned below a portion of the circumference of one of said feed rolls, means for adjusting the heights of said receptacle for single sheets and said receptacle for folded sheets, means for adjusting the size of said receptacle for folded sheets to the size of the folded sheet to be used in the device, an additional feed roll couple positioned forwardly of said receptacle for folded sheets, suction means located above said receptacle for single sheets, additional suction means located above said receptacle for folded sheets, arm members adapted to raise said suction means simultaneously, said arm members being actuated by the same timing mechanism so that the movement of said suction means is adapted to carry one of the single sheets at a time over said first-named feed roll couple and simultaneously to raise one side of one of said folded sheets so that one of said single sheets is inserted between the fold of one of said folded sheets, further suction means adapted to convey said folded sheets after insertion of said single sheets over said additional feed roll couple, an additional receptacle adapted to hold said folded sheets after insertion of said single sheets positioned forwardly of said additional feed roll couple, means driving said first-named feed roll couple and said additional feed roll couple, and means driving said suction means.

4. A device for inserting a number of single sheets into a number of folded sheets comprising a receptacle for the single sheets, a feed roll couple positioned forwardly of said receptacle for single sheets, one of said feed rolls being provided with a circumferential groove, air blast means located within said groove in said feed roll, a receptacle for folded sheets positioned forwardly of said feed roll couple, the topmost folded sheet disposed in said receptacle being positioned below a portion of the circumference of one of said feed rolls, means for adjusting the heights of said receptacle for single sheets and said receptacle for folded sheets, an additional feed roll couple positioned forwardly of said receptacle for folded sheets, suction means located above said receptacle for single sheets, additional suction

means located above said receptacle for folded sheets, arm members adapted to raise said suction means simultaneously, said arm members being actuated by the same timing mechanism so that the movement of said suction means is adapted to carry one of the single sheets at a time over said first-named feed roll couple and simultaneously to raise one side of one of said folded sheets so that one of said single sheets is inserted between the fold of one of said folded sheets, further suction means adapted to convey said folded sheets after insertion of said single sheets over said additional feed roll couple, an additional receptacle adapted to hold said folded sheets after insertion of said single sheets positioned forwardly of said additional feed roll couple, means driving said first-named feed roll couple and said additional feed roll couple, and means driving said suction means and air blast means.

5. A device for inserting a number of single sheets into a number of folded sheets comprising a receptacle for the single sheets, a number of single sheets disposed within said receptacle, a feed roll couple positioned forwardly of said receptacle for single sheets, one of said feed rolls being provided with a circumferential groove, air blast means located within said groove in said feed roll, a receptacle for folded sheets positioned forwardly of said feed roll couple, a number of folded sheets disposed within said receptacle, means for adjusting the heights of said receptacle for single sheets and said receptacle for folded sheets so that the topmost sheet within the receptacle for single sheets will be at approximately the same level of the topmost sheet within the receptacle for folded sheets, and the topmost sheet within the receptacle for folded sheets will be positioned below a portion of the circumference of one of the feed rolls of said feed roll 40

couple, an additional feed roll couple positioned forwardly of said receptacle for folded sheets, a plurality of suction feet located above said receptacle for single sheets, an additional plurality of suction feet located above said receptacle for folded sheets, arm members adapted to raise said suction feet simultaneously, said arm members being actuated by the same timing mechanism so that the movement of said suction means is adapted to carry one of the single sheets at a time over said first-named feed roll couple and simultaneously to raise one side of one of said folded sheets so that one of said single sheets is inserted between the folds of one of said folded sheets, further suction means adapted to convey said folded sheets after insertion of said single sheets over said additional feed roll couple, an additional receptacle adapted to hold said folded sheets after insertion of said single sheets positioned forwardly of said additional feed roll couple, means driving said first-named feed roll couple and said additional feed roll couple, and means driving said suction means and air blast means.

6. A device as described in claim 5 wherein the 25 arm members actuating the suction feet located above said receptacle for single sheets travel upwardly and pivotally so that the suction feet travel both upwardly and forwardly.
